SWIVEL CONNECTION FOR RAILWAY
SWITCHES AND THE LIKE

James C. Mock, Detroit, Mich.

Application June 4, 1938, Serial No. 211,719

4 Claims. (Cl. 246—452)

The invention relates, in general, to railway track equipment and, more particularly, to a swivel construction for connecting track rods to the track points of railway switches, derailing switches and the like.

In general, such swivel constructions comprise a clip member secured to the track point and a dog member secured to the track rod, with a pivot device connecting the dog and clip. According to one form which the invention may assume, the clip member of the swivel connection is provided with a sectional bearing construction comprising a base section and a removable strap section. The dog is provided with a journal supported at both its upper and lower ends by a forked brace. The journal of the dog is disposed between the base and strap of the clip bearing, the strap extending through a recess between the journal and brace of the dog.

The swivel construction according to the invention may be used at the extreme end of the switch point and also, if desired, at intermediate points along the switch points. The invention is illustrated as applied to single switches, but it will be understood that it is also applicable to other uses, as for example, to derailing switches, to double slip switches, both to the switch points and center points thereof, to single slip switches, and to the movable center points of frog crossings.

The invention also consists in certain new and original features of construction and combination of parts hereinafter set forth and claimed.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which

Fig. 1 is a plan view of a single switch with the invention applied thereto;

Fig. 2 is a vertical section taken on the line 2—2 of Fig. 1;

Figs. 3 and 4 are vertical sections taken on the lines 3—3 and 4—4 of Fig. 1;

Fig. 5 is a perspective of the base member of the type of clip used at the extreme end of the switch point;

Fig. 6 is a perspective of the base member of the type of clip used at intermediate points along the switch point;

Fig. 7 is a perspective of the strap member in-

corporated with the base members of Figs. 5 and 6 to form complete bearings;

Fig. 8 is a perspective of the dog member; and Fig. 9 illustrates a special type of nut.

In the following description and in the claims, various details will be identified by specific names for convenience, but they are intended to be as generic in their application as the art will permit.

Like reference characters denote like parts in the several figures of the drawings.

In the drawings accompanying and forming part of this specification, certain specific disclosure of the invention is made for purposes of explanation, but it will be understood that the details may be modified in various respects without departure from the broad aspect of the invention.

Referring now to the drawings and, more particularly, to Fig. 1, a track construction is shown made up of stock rails 10 and 11, switch points 12 and 13, these rails resting on the usual tie plates (not shown), which in turn are supported by the usual railroad ties 15. The tie plates are omitted for simplicity of illustration. The stock rails 10 and 11 are preferably of standard T-section and the switch points 12 and 13 may also be of standard T-section suitably planed and shaped in accordance with the usual practice of making switch points.

Although a certain type of switch point is shown for purposes of illustrating the invention, it will be understood that other suitable switch point constructions may be used.

The switch points are connected by switch rods indicated in general by 16 and 17. The switch rod 17 connects the extreme ends of the switch points and the switch rod 16 connects the switch points at intermediate places. Any number of intermediate switch rods 16 may, of course, be used.

The switch rods 16 and 17 may be made of the usual flat bar steel disposed vertically or edge-wise. The switch rods may be made in one piece or they may be made in sections with an insulating joint in the middle in accordance with well known practice. If desired, various forms of operating rods may be connected to the switch rods, operating rod 18 extending to a switch stand (not shown) and operating rod 19 extending to a locking device (not shown). Rods 18 and 19 are connected to rods 16 and 17 by boxes 20 and 21 which, in the event switch rods 16 and 17 are made in two pieces, may also incorporate insulating joints. Switch rods 16 and 17 are connected to switch points 12 and 13 by vertical swivel connections 22 and 23.

- Referring now to Figs. 3, 4 and 6-9, swivel connection 22 comprises a base member 26 (Fig. 6) having a lower flange 30 and a bearing section 32 provided with a seat 31. The base member 26 is bolted to the switch point 12, for example, by bolts 42 passing through strengthening plates 28 and 29 and the web of the switch point in a manner described hereinafter more in detail. A strap 33 (Fig. 7), having a bearing section 34, cooperates with bearing section 32 to complete the bearing.
- The dog member (Fig. 8) comprises a holder 36 opening downwardly to receive the switch rod 16. The dog also comprises a journal 37 connected to the holder 36 by a forked brace 38 providing a recess 40. A strengthening web 39 is further provided to reinforce the construction. Nut and bolt assemblies 41 securely connect the vertical switch rod 16 to the holder 36.
- 20 The swivel connection is assembled as follows: Special nuts 43 (Fig. 9) are threaded on bolts 42 to rigidly secure the base 26 to the switch point. The nut 43 is a hexagonal nut having grooves or recesses 44 cut into the ends of the hexagonal faces to facilitate tightening of the nut. Thus, the nut may be adjusted either by the usual open end wrench or by engaging an edged instrument, such as a screw driver, in the grooves 44 and hitting with a hammer.
- 25 To complete the assembly, the strap 33 is inserted through the recess 40 of the dog and then threaded onto the bolts 42 with the journal 37 seated between the bearing sections 32 and 34. If desired, washers 45 may be located between the special nuts 43 and the strap 33 to provide proper bearing clearance between the journal 37 and bearing 32, 34. Nuts 46 are then threaded onto bolts 42 to securely clamp the strap 33 to the base 26.
- 30 Referring now to Figs. 1, 2 and 5, special swivel connections 23 are provided for the ends of the switch points 12 and 13. As shown in Fig. 5, the modified form of base member, indicated by 50, is provided with a bearing section 53, corresponding to bearing section 32, an extension 51 for connection to the switch point and another extension 52 for connection to a stud 61. The stud 61 supports a socket member 62 connected to rod 63 extending to special track apparatus, as for example, a switch circuit controller. The bearing section 53 is provided with a seat 54. This swivel connection uses the same strap 33 (Fig. 7) and the same dog (Fig. 8) as used in the first swivel construction described above.
- 35 The end swivel construction is assembled as follows:
- Nut and bolt assembly 55 passes through the end of extension 51 and the reenforcing plates and web of the switch point 13, for example. The base 50 is further secured in position by the bolt 56 also passing through the switch point 13. The special hexagonal nut, indicated by 57, is similar in construction to that of Fig. 9, and is threaded onto bolt 56, as indicated in Fig. 1, to clamp base 50 to the switch point. Nut 58 is threaded on bolt 56 to hold strap 33 in position.
- The stud 61 is secured to extension 52 by bolt and nut assemblies 59 and 60. Assembly 59 also passes through the strap 33 to clamp it in position. In this construction, as in the construction of swivels 22, washers (not shown) may be interposed between the strap 33, on the one hand, and the special nut 57 and extension 52, respectively, on the other hand, to provide proper clear-

ance for the working of the journal of the dog member in the bearing of the clip.

Thus, swivel assemblies have been provided which are rigid, dependable and easy to operate. The parts are easily accessible both for inspection and for adjustment, the special hexagonal nuts 43 and 57 being especially adapted for easy adjustability. It will be noted that all bolt assemblies are horizontally disposed, making them easily inspectable by the track walker so that any breaking or other failure thereof may be easily noticed by the track walker.

The bearing and journal construction is especially advantageous in that the journal is supported at both ends by the forked brace 38. The seats 31 and 54 of the clips take the downward thrust of the journals 37 due to the weight of the switch rods. Proper bearing relation is insured by using the proper size washers 45. Sufficient tightness is obtained between the journals and bearings to insure rigidity of support to the switch points and yet to provide easy operation when the switch points are operated by the switch stand or other switch operating mechanism.

It will be noted that in both the end swivel 25 connections 23 and the intermediate connections 22 the swivel bearings and journals are located above the level of the base flange of the switch points 12 and 13 and close to the webs to apply the bracing force as near as possible to the top 30 of the switch points while still allowing the necessary clearances for the wheel flanges. This provides maximum bracing action against tipping of the switch points. It will be noted further that substantially no vertical movement is permitted 35 between the journals 37 and their bearings and that the switch rods 16 and 17 pass closely under the base flanges of the stock rails 10 and 11, to effectively hold down the switch points 12 and 13 with respect to the stock rails 10 and 11.

While certain novel features of the invention have been disclosed and are pointed out in the annexed claims, it will be understood that various omissions, substitutions and changes may be made by those skilled in the art without departing 45 from the spirit of the invention.

What is claimed is:

1. In railway track equipment, a stock rail, a movable rail point having a web and a base flange, a rod for moving said rail point and bracing it against tipping, a clip comprising an attaching member secured to said web and a swivel holder disposed above the level of said flange and close to the line of said web, a dog comprising a rod holder secured to said rod, said dog also comprising a brace member connecting said rod holder and straddling the top and bottom of said swivel holder, a vertical pivot member connected to said brace member at top and bottom and to said swivel holder to provide swivel movement of 50 said dog and clip in a horizontal plane and to provide effective support against tipping of said rail point.
2. In railway track equipment, a stock rail, a movable rail point having a web and a base flange, a rod for moving said rail point and bracing it against tipping, a clip comprising an attaching member secured to said web and a bearing section having a substantially vertical bearing surface disposed above the level of said base 55 flange and close to the line of said web, a dog comprising a journal portion disposed against said bearing surface, said dog also comprising a rod holder secured to said rod, said dog further comprising a forked brace member integral with 70
- 75

said rod holder and integral with the top and bottom of said journal portion thereby providing an opening, a bearing section having a bearing surface extending through said opening and secured to said clip to hold said bearing sections together with the journal portion journalled between said bearing surfaces for easy pivotal movement in a horizontal plane, said forked brace member providing effective support against tipping of said rail point.

3. In railway track equipment, a stock rail, a movable rail point having a web and a base flange, a rod for moving said rail point and bracing it against tipping, a clip comprising an attaching member bolted to said web and a bearing section having a substantially vertical bearing surface and a substantially horizontal seat at the lower end of said bearing surface, a dog comprising a journal portion disposed against said bearing surface and resting on said seat, said dog also comprising a rod holder secured to said rod, said dog also comprising a forked brace member integral with said rod holder and integral with the top and bottom of said journal portion thereby providing an opening, a bearing section having a bearing surface extending through said opening and bolted to said clip to hold said bearing sections together with the journal portion journalled between said bearing surfaces for easy pivotal movement in a horizontal plane, said forked

brace member providing effective support against tipping of said rail point.

4. In railway track equipment, a stock rail, a movable rail point having a web and a base flange, an edgewise disposed rod for moving said rail point and bracing it against tipping, a clip comprising an attaching member bolted to said web and a bearing section having a substantially vertical bearing surface and a substantially horizontal seat at the lower end of said bearing surface, said seat being disposed above the level of said base flange with said bearing section close to the line of said web, a dog comprising a journal portion disposed against said bearing surface and resting on said seat, said dog also comprising a depending rod holder having a vertically extending recess in which said rod is disposed and bolted thereto, said dog also comprising a forked brace member integral with said rod holder and integral with the top and bottom of said journal portion thereby providing an opening, a bearing section having a bearing surface and extending through said opening and bolted to said attaching member to hold said bearing sections together with the journal portion journalled between said bearing surfaces for easy pivotal movement in a horizontal plane, said forked brace member providing effective support against tipping of said rail point.

JAMES C. MOCK. 30
